UNITED STATES PATENT OFFICE.

ROY S. SMITH, OF CAIRO, ILLINOIS.

CAR-DOOR OPERATING AND LOCKING DEVICE.

Application filed February 4, 1927. Serial No. 165,912.

This invention relates to new and useful improvements in means for facilitating the opening and closing sliding car doors, and also to permit such doors to be locked in fully open or closed position, or any point therebetween.

The primary object of the invention resides in the provision of means that may be readily associated with a car and its sliding door so as to permit the door to be opened or closed regardless of the tightness of the same and to also permit of the car being sealed in locked or slightly opened position.

With the foregoing and other objects in view as the nature of the invention will be better understood, the same comprises the novel form, combination and arrangement of parts hereinafter more fully described, shown in the accompanying drawings and claimed.

In the drawings:

Figure 1 is a fragmentary side elevation of a freight car and its sliding door equipped with a device constructed in accordance with the present invention.

Figure 2 is a detail vertical section taken substantially upon the line 2-2 of Figure 1.

Figure 3 is an enlarged view of the device as associated with a car and door.

Figure 4 is a view taken substantially upon the line 4-4 of Figure 3 looking downwardly.

Figure 5 is a similar view taken substantially upon the line 5-5 of the same figure, and

Figure 6 is a fragmentary elevation of a slightly modified form of device as actually in use.

First having reference to the Figures 1 to 5 the freight car is designated generally by the reference character 5, while one of its sliding doors is designated by the reference character 6. In carrying out my invention, I securely bolt to the side of the car beneath the door 6 a horizontal angle bar 7 that may serve as a support for the lower end of the door 6 and that is formed in its top side with spaced openings 8^a throughout the length thereof. Rigidly secured to the car door 6 directly above the lower edge thereof and at any predetermined point throughout its width is a vertical guide sleeve 8 within which is loosely arranged an

elongated pin 9 headed at its upper end as at 10 and provided at its lower end with a lateral lug 11 for the purpose of preventing the entire disengagement of this pin from said guide sleeve.

Rigidly secured to the extreme lower edge of the door 6 directly beneath said guide sleeve 8 is a collar 12 through which the pin 9 may freely move. Pivotedly secured to this collar is the plate-like end 13 of a depending hand lever 14. The plate end 13 of this handle is formed above the collar 12 at opposite edges with inwardly projecting ears 14^a-14^a that are vertically bifurcated so as to permit the inner ends of pull fingers 15-15 to be pivotally secured thereto as at 16-16. The extreme inner ends of these fingers are of widened diameter as indicated in Figure 3. The pivots 16-16 pass through these fingers 15-15 at a point slightly spaced from the inner corners thereof, and said inner corners of the fingers are beveled as suggested by the dotted lines in Figure 3 so that when the same are swung downwardly to the full line position and the pin 9 dropped between the ears 14^a-14^a of the lever 14, said pin will engage these tapered edges and prevent the swinging of the fingers in either direction. On the other hand when the pin is raised above the inner ends of the fingers, the same may be swung upwardly to the dotted line position and by again engaging the pin downwardly therebetween, said fingers will be locked in this position, all for a purpose and in a manner hereinafter more fully described.

The free ends of the pull fingers 15-15 are formed at their inner edges with right angular double tapered lugs 17-17 for engagement with the openings 8^a of the rail 7. Obviously, when the pin 9 is raised above the inner ends of the fingers, a movement of the lever will force the door to open or closed position, depending upon which of the fingers 15 is dropped downwardly so as to permit of the engagement of its lug within the openings of the rail.

It is of course apparent that after the lever 14 has been swung to its limit of movement in one direction for causing a pull upon the operative finger 15, the return movement of the lever will cause the lug 17 of that finger to ratchet over the openings

in the rail to permit a new grip to be secured thereon within a new opening so that the operation may be repeated.

In order that the vertically movable pin 5 9 may be secured within a predetermined opening of the rail 7 and for preventing the release of the fingers 15—15 from the rail, said pin is formed at a point beneath the 10 guide sleeve 8 with a slot 18, while depending from opposite sides of the guide sleeve 8 are lugs 19—19 that also have slots therein in registration with the slot 18 in order that a seal 20 may be passed therethrough.

The form of the invention disclosed in 15 Figure 6 is substantially identical to the form disclosed in the other views with the exception of the fact that the upper plated end 13' of this lever 14' has pivotally attached to one side only one finger 15' similar 20 in all respects to the fingers 15—15 in the other form of the invention with the exception that the lower end thereof is provided with a depending untapered lug 17' for engagement within the openings of the rail 7'. 25 In this form of the invention when the pin 9' is raised, a swinging movement of the lever 14' will create a pull upon the fingers for opening the door to an extent equivalent to the degree of movement of the lever, whereas on the other hand a reversal of 30 movement of the lever will cause a push upon said finger 15' for moving the door in a closed direction to a similar degree.

It will thus be seen that I have provided 35 a highly novel, simple, and efficient means for facilitating the opening and closing of sliding car doors, and that is also adapted for permitting the door to be locked and sealed in partially sealed or fully closed position, and even though I have herein shown 40 and described the invention as consisting of certain detail structural elements, it is nevertheless to be understood that some changes may be made therein without affecting the 45 spirit and scope of the appended claims.

Having thus described the invention, what I claim is:—

1. In a sliding car door operator, a rail 50 secured to the car beneath the door and formed throughout its length with abutments, a lever pivoted to the door adjacent the lower edge thereof, a finger pivoted at its inner end to the upper pivoted end of the lever, a pawl formed on the outer free end 55 of the lever for engagement with the abutments on the rail, whereby the door may be moved to open or closed position by a swinging movement of the lever, and a sliding bolt carried by the door for cooperation with the pivoted end of the finger for locking the 60 same against swinging movement.

2. In a sliding car door operator, a rail 65 secured to the car beneath the door and formed throughout its length with abutments, a lever pivoted to the door adjacent

the lower edge thereof, a finger pivoted at its inner end to the upper pivoted end of the lever, a pawl formed on the outer free end of the lever for engagement with the abutments on the rail, whereby the door may be 70 moved to open or closed position by a swinging movement of the lever, a sliding bolt carried by the door for cooperation with the pivoted end of the finger for locking the same against swinging movement, and means 75 carried by the pivoted end of the lever for cooperation with the sliding bolt to lock the lever against swinging movement.

3. In a sliding car door operator, a rail secured to the car beneath the door and formed throughout its length with abutments, a lever pivoted at its inner end to the upper pivoted end of the lever, a pawl formed on the outer free end of the lever for engagement with the abutments on the rail, whereby the door may be moved to open or closed position by a swinging movement of the lever, a sliding bolt carried by the door for cooperation with the pivoted end of the finger for locking the same against swinging 80 movement, means carried by the pivoted end of the lever for cooperation with the sliding bolt to lock the lever against swinging movement, said last mentioned means comprising 85 a pair of ears extending laterally from the inner face of the pivoted lever on opposite sides of the slidable bolt.

4. In a sliding car door operator, a rail secured to the car beneath the door and formed throughout its length with abutments, a lever pivoted to the door adjacent the lower end thereof, a finger pivoted at its inner end to the upper pivoted end of the lever, a pawl formed on the outer free end of the lever for engagement with the abutments on the rail, whereby the door may be moved to open or closed position by a swinging movement of the lever, a sliding bolt carried by the door for cooperation with the pivoted end of the finger for locking the same against swinging movement, means carried by the pivoted end of the lever for cooperation with the sliding bolt to lock the lever against swinging movement, said last mentioned means comprising a pair of ears 100 extending laterally from the inner face of the pivoted lever on opposite sides of the slidable bolt, and means for holding the bolt in a raised inoperative position to permit the swinging movement of the lever as well 105 as the finger.

5. In a sliding car door operator, a rail secured to the car beneath the door and formed throughout its length with abutments, a lever pivoted to the door adjacent its lower edge, a finger pivoted at its inner end to the upper end of the lever, a member at the lower end of the finger for engagement with the rail abutments, whereby the door may be moved to open or closed posi- 115 120 125 130 135

tion by swinging of the lever in the proper direction, means whereby the lever may be locked against swinging movement, said means being also operable to prevent the swinging of the finger upon said lever, said means comprising a sleeve arranged upon the car door directly above said lever, an elongated pin vertically slideable through the

sleeve for engaging the upper end of the lever and for engaging in back of the end 10 of the finger, said sleeve and the pin being formed with openings in registration when the pin is dropped so as to permit the pin to be sealed to said sleeve.

In testimony whereof I affix my signature.
ROY S. SMITH.
